SHEALY L. ODELL, OF GREENSBORO, NORTH CAROLINA, ASSIGNOR OF FORTY ONE-HUNDREDTHS TO ALVA GALLIMORE, OF GREENSBORO, NORTH CAROLINA.

LOOM.

1,120,522.

Specification of Letters Patent.

Patented Dec. 8, 1914.

Application filed October 23, 1913. Serial No. 796,878.

To all whom it may concern:

Be it known that I, SHEALY L. ODELL, a citizen of the United States, residing at Greensboro, in the county of Guilford and State of North Carolina, have invented certain new and useful Improvements in Looms; and I do declare the following to be a full, clear, and exact description of the invention, such as will enable others skilled in the art to which it appertains to make and use the same.

This invention relates to weaving, and more especially to the driving and lay motions for looms; and the object of the same is to produce a unitary mechanism which will simultaneously actuate the pickers and swing the lay and will do away with the picker sticks, reduce the number of parts, and simplify the entire structure. This object is carried out by the mechanism set forth in the following specification and shown in the drawings wherein—

Figure 1 is a front elevation of a device constructed in accordance with my invention with the parts at rest, some of the parts being broken away for purposes of better illustration. Fig. 2 is a fragmentary rear elevation thereof. Fig. 3 is a horizontal section on the line 3—3 of Fig. 1, and Fig. 4 is a plan view. Fig. 5 is a vertical section on the line 5—5 of Fig. 1. Fig. 6 is a partial front elevation showing the parts in motion and illustrating the shuttle as just starting toward the left, and Fig. 7 is a vertical section on the line 7—7 of Fig. 6. Fig. 8 is a detail of a modified form of picker arm.

Inasmuch as my improvement is applicable to a particular part of a loom, only such parts will be illustrated and described as are absolutely necessary to the full and complete understanding of the case.

B designates a suitable base such as the floor, or sills thereon, and F the framework or swords pivoted at P to said base and carrying the lay L along which the shuttle S is reciprocated by the picker mechanism as the lay swings to and fro as usual. Other well known features of the ordinary loom need not be illustrated or described, and the action of this machine does not differ from those now in common use.

Referring now to the details of the present invention, a rotating shaft 1 is mounted in bearings 2 rising from the base B and

carries a cam 3. This cam is in effect a disk carried on the shaft and having a winding groove or cam slot 4 in its peripheral edge. Loosely mounted in this groove is a pin or roller 5 which depends from a bracket 6 carried by the frame F, and in the present instance the bracket is shown in the shape of an arch which rises from the lower cross bar 7 of said frame although this detail is not necessary. At each revolution of the shaft 1 the groove 4 engaging the roller 5 will swing the frame F and with it the lay L to and fro. Fast on said shaft adjacent the cam is an arm 10 preferably having a roller 11 at its outer end, and this arm rotates within a ring 12 having at diametrically opposite points therein inwardly projecting cams 13 and 13' respectively with rather abrupt engaging faces 14 which are struck by the roller 11 as the arm rotates with the shaft 1. The ring is secured to and forms the lower portion of a lever 15 which is pivoted on a bracket 16 at the point 17 just above the ring as best seen in Figs. 1 and 6, the bracket also in this case being shown as an arch rising rigidly from the lower cross bar 7 of the frame F. The upper end of the lever is forked as at 18 and loosely receives a pin 19 on the picker rod 20. The latter carries the pickers 85 which actuate the shuttle as usual, and while they may be of any desired detailed structure I prefer to make them as follows: The rod 20 slides through guides 21 mounted on the frame F and carries at each extremity a picker arm 22 which rises through a slot 23 in the end of the lay and is faced with a suitable cushion 24. The arm 22 may be of metal having a socket at its lower end secured by set screws 25 to the extremity of 95 the rod 20; or, as shown in Fig. 8, the head 26 may be of an L-shaped piece of metal connected in the same way or in any suitable way with the extremity of the rod, and the arm may be of wood as at 27 and will 100 rise through the slot and carry the cushion as described. The latter is for the well known purpose of receiving the impact of the point of the shuttle as it is thrown from the opposite picker across the lay.

Another detail which I preferably employ is a buffer to check the inward movement of the picker with yielding force. Into the end of the lay at the inner end of the slot 23 is bored a hole 30 which is by pref-

erence lined with a piece of metal tubing as indicated at 31, and within the socket thus formed is seated a coiled expansive spring 32 whose outer end is covered by a head 33 having a stem 34 projecting into the spring. 5 When now the picker is moved suddenly inward to impart an impulse to the shuttle S, it strikes the head 33 and the latter compresses the spring so that, if the parts are 10 properly made, said picker will not contact with the inner end of the slot and there will be no sudden jar upon the parts.

With the above construction the operation of this device is as follows, starting with the 15 parts at rest as seen in Fig. 1: Power is applied from any suitable source to the main shaft 1 and the crank arm 10 and cam 3 turn through a quarter revolution to the position shown in Fig. 6. This shows the parts after 20 the roller 11 has traveled up the engaging face 14 of the cam 13 so that the entire ring swings to the right from the pivot 17 and the upper portion of the lever 15 is moved to the left, and hence the fork 18 of said lever 25 has moved the picker rod 20 and the right picker arm 22 has forced the shuttle S along the lay. Meanwhile also the cam has turned to the position indicated in Fig. 7, and its groove 4 engaging the roller 5 has swung the 30 lay so that the advancing shuttle has moved between the shed of the warp threads and has laid the weft thread therein. Arriving at the opposite end of the lay, the point of the shuttle strikes the cushion 24 on the 35 other picker arm, and the force of its impact is cushioned and the shuttle comes to rest rather than rebounding. As the crank arm 10 continues its movement from the position shown in Fig. 6 in a direction as indicated by the arrow in said figure, the cam 3 will, of course, also be rotated in this 40 particular direction and the lay will be swung in the opposite direction as a result thereof. The swinging of the arm 10 in the 45 direction of the arrow as seen in Fig. 6, will permit the free end of said arm to properly engage the member 12, so as to also dispose the same in the direction opposed to that disclosed in Fig. 6, or in other words, to the 50 left hand side of the frame. The roller on the outer end of the arm will, of course, perform the actual contacting with the ring and will obviously contact with the engaging face of the cam 13'.

55 Owing to the weakness of the weft threads it is not ordinarily considered advisable to start the shuttle along its course too suddenly, and therefore no harm will be done if the roller strikes within the ring 12 or if, 60 in fact, the face 14 of the cam therein is shaped with this end in view. It is quite obvious that the cam 3 could be replaced by another having a different groove 4, or that it could be set on the shaft 1 adjustably so 65 that it could be adjusted in timed relation to

the action of the cams within the ring 12. However, matters of adjustment are not necessary to the successful operation of the present invention, and I do not wish to be limited to them nor to details of construction or materials or proportions of parts. 70

What is claimed as new is:

1. In a loom, the combination with the swinging lay-frame, and the picker rod reciprocating therein; of a power shaft extending through the lay-frame, a cam thereon having a groove in its face, a bracket in said frame having a pin engaging said groove, an arm fast on said shaft, a ring pivoted on the frame and encircling said arm, said ring having oppositely disposed cams adapted to be struck by the outer end of said arm, and connections between said ring and the picker rod. 75

2. In a loom, the combination with the swinging lay-frame, and the picker rod reciprocating therein; of a power shaft extending through the lay-frame, a cam thereon having a groove in its face, a bracket in said frame having a pin engaging said groove, an arm fast on said shaft, a ring encircling the arm and having oppositely disposed cams adapted to be struck by its outer end, a lever having its upper end connected to said picker rod and its lower end attached to said ring, a bracket carried by the lay-frame, and a pivot connecting this bracket with the lever. 85

3. In a loom, the combination with the lay, the swinging frame therefor, and the picker rod movably mounted therein; of a power shaft, a cam thereon having a groove in its face, a bracket in said frame having a pin engaging said groove, an arm fast on said shaft, a ring encircling the arm and having oppositely disposed cams adapted to be struck by the outer end of said arm, a lever extending rigidly upward from the top of said ring, loose connections between the upper end of the lever and the picker rod, 100 an arch rising from the lower cross bar of the lay-frame, and a pivot between said arch and the lever at its point of juncture with the frame. 105

4. In a loom, the combination with the swinging lay, and the picker rod reciprocating therein; of a horizontal power shaft, a cam thereon, connections between the cam and the lay-frame for swinging the latter, an arm projecting rigidly from said shaft 115 and having a roller at its outer end, a ring surrounding said arm and having oppositely disposed cams adapted to be engaged by said roller, a lever extending rigidly upward from the top of said ring, loose connections between the upper end of the lever and the picker rod, 120 an arch rising from the lower cross bar of the lay-frame, and a pivot between said arch and the lever at its point of juncture with the frame. 125

5. In a loom, the combination with the swinging lay and the picker rod reciprocating therein; of a horizontal power shaft, a cam thereon, connections between the cam 5 and the lay-frame for swinging the latter, an arm projecting rigidly from said shaft and having a roller at its outer end, a ring surrounding said arm and having oppositely disposed cams adapted to be engaged by said 10 roller, a lever rising rigidly from the ring and having a forked upper end, a bracket on the lay-frame to which said lever is pivoted, and a pin projecting from the mid-length of the picker rod through the fork in 15 said lever.

6. In a loom, the combination with the base, a swinging lay whose frame is pivoted in the base, guides on said frame, and the picker rod slidably mounted through said 20 guides; of bearings rising from said base, a horizontal power shaft journaled in said bearings, means in connection with the shaft and disposed between the bars of the lay frame for swinging the latter as the shaft 25 rotates, an arm projecting rigidly from said shaft and carrying a roller, a ring surrounding the roller and having inwardly projecting cams adapted to be struck by said roller, a lever rising rigidly from the top of the 30 ring and loosely connected with said picker rod, a bracket within the lay-frame, and a pivot between said lever and bracket.

7. In a loom, the combination with a stationary base, a frame mounted for pivotal 35 movement thereon, a lay carried on the

frame and a picker rod movably mounted on said frame; of a drive shaft extending through the frame and having its axis in a plane at right angles to the pivotal axis of said frame, means in connection with said 40 shaft and the frame for oscillating the latter on the base as said shaft is rotated, a bracket secured to said frame and having the shaft disposed therethrough, a lever fulcrumed on the upper portion of said bracket 45 and having the upper end thereof arranged in connection with said picker rod to reciprocate the latter as the lever is oscillated on its fulcrum point, a ring-like member formed on the lower fulcrumed portion of 50 said lever and projecting therebelow to receive said shaft therethrough, the inner periphery of said ring-like member being provided with cams at diametrically opposite points thereon, an arm carried on the shaft 55 to rotate therewith and disposed within the space inclosed by said ring-like member and a roller carried on the outer end of said arm to contact with the inner peripheral edge of said ring-like member and the cams thereon whereby to oscillate said lever and actuate the picker rod as said shaft is rotated. 60

In testimony whereof I have hereunto set my hand in presence of two subscribing witnesses.
